UNITED STATES PATENT OFFICE.

JOHN DOWNIE, OF SEATTLE, WASHINGTON.

GRAVITY DROP.

Application filed March 7, 1922. Serial No. 541,735.

To all whom it may concern:

Be it known that I, JOHN DOWNIE, a citizen of the United States, residing at Seattle, in the county of King and State of Washington, have invented a certain new and useful Improvement in Gravity Drops, of which the following is a specification.

My invention relates to improvements in gravity drops for lowering heavy articles and the object of my invention is to provide 10 a gravity drop by which heavy articles may be quickly and easily lowered any desired distance and the gravity drop carriage returned to the upper end of a shaft in which 15 it operates without the use of any externally applied power the weight of the heavy article that is being lowered serving to raise certain counterweights by which the drop carriage is afterwards moved from the 20 lower to the upper end of the drop shaft when the heavy article has been removed therefrom.

Another object is to provide a vertically 25 movable gravity drop having a compensating or shifting weight in the form of a heavy chain one end of which is attached to the drop carriage and the other end of which is attached to a counterweight in such a manner as to cause the weight of the 30 chain to be gradually shifted or transferred from the carriage to the counterweight or from counterweight to the carriage as the two move in opposite direction in the shaft, the weight of the chain being always transferred from the downwardly moving member 35 to the upwardly moving member.

Another object is to provide novel brake 40 means that are arranged to be applied as the gravity drop carriage approaches the limit of its downward movement to check the speed of descent of the carriage.

Other and more specific objects will be apparent from the following description taken in connection with the accompanying 45 drawings.

The device shown and described in this application is designed especially for use in lowering semi-cylindrical stereotype plates of the form commonly used in news- 50 papers, printing plants, but it will be understood that such device may be readily adapted for lowering various other forms of heavy articles without altering the general plan of construction and method of 55 the same.

In the accompanying drawings, Figure 1 is a somewhat diagrammatic view partly in vertical section and partly in elevation of a gravity drop shaft provided in accordance with my invention, the drop carriage being 60 shown at the upper end of the shaft;

Fig. 2 is a similar view showing the drop carriage at the lower end of the shaft;

Fig. 3 is a fragmentary sectional view of the bottom end of the drop shaft showing 65 certain curved guideways and certain catch and release means in elevation;

Fig. 4 is a detached view in perspective of a detail of the invention;

Fig. 5 is a view partly in section and 70 partly in side elevation of the drop carriage;

Fig. 6 is a view in front elevation of the drop carriage portions of the drop shaft 75 being shown in section;

Fig. 7 is a view in cross-section on a reduced scale substantially on broken line 7, 7 of Fig. 6; and

Figs. 8 and 9 are fragmentary views 80 partly in section and partly in elevation illustrating different details of my invention.

Referring to the drawings, throughout 85 which like reference numerals designate like parts, the numeral 10 indicates a vertically arranged drop shaft of rectangular cross sectional shape and having on opposite sides continuous trackways 11 on which a drop carriage is guided for vertical movement.

The gravity drop carriage is formed, in 90 part, of two vertical spaced, parallel side members 12 that are each provided near their top and bottom ends with channel shaped guide pieces 13 that fit over and slide upon the trackways 11 and that are rigidly secured together at the top and bottom by transverse upper and lower frame bars 14 and 15 respectively.

A frame for the support of certain brake 100 devices and brake operating mechanism is formed by a horizontal bar 16 that is disposed parallel with and at a distance from the upper frame bar 14 and that is rigidly secured to the carriage frame by angular 105 truss braces 17 and horizontal plates or bars 18 which are provided at both ends.

Mounted within the frame of the drop carriage and movable vertically with respect thereto is a cradle for the reception of the 110

load or heavy articles, which may be semi-cylindrically shaped stereotype plates 20. The cradle is preferably formed of front and rear angle bars 21 and 22 each having 5 horizontal portions that extend crosswise of the carriage frame and end portions that are bent upwardly in convergent relation and are rigidly secured together at their upper extremities by short angle bar sections 23. The angle bar sections 23 are provided with outwardly protruding spaced apart lugs 24 that fit on opposite sides of the inwardly protruding flanges of the side frame members 12 and guide the cradle for 10 vertical movement on the carriage frame.

The upper ends of the members 21 and 22 on opposite sides of the cradle are rigidly secured together by transverse angle bars 25 and the lower horizontal portions of the members 21 and 22 are connected by spaced angle bars 26 and 27 that are disposed adjacent to the opposite sides of the cradle and have their horizontal flanges turned outwardly so that the edges of the stereotype plate 20 may rest thereon as shown in Fig. 6, and be guided by the vertical flanges of such bars 26 and 27. The vertical flanges of the bars 26 and 27 are bent inwardly as at 28 at their front ends and serve as guides to 15 assist in positioning the stereotype plates 20 on the cradle.

The bars 26 and 27 connected with each other midway of their length by a cross bar 30 whose ends project outwardly past the bars 26 and 27 and are notched as shown in Fig. 7, so that they fit over the flanges of the frame members 12 and co-operate with the lugs 24 in supporting the cradle so that it may be moved vertically with respect to the 20 carriage frame.

The cradle is arranged to be supported from below by a bent supporting rod, as shown, comprising longitudinally aligned bearing portions 31 that are connected by an arch-like supporting portion 32 and one of which is bent at right angles to form a lever arm 33 whose outer end is again bent at right angles and is provided with a roller 34. The bearing portions 31 are arranged to be journaled in bearing brackets 35 on the cross bar 15 and the arched portion 32 is provided with a suitable lug 36 to which a tension spring 37 may be secured.

The tension spring 37 is connected with the upturned end of a bracket 38 that is rigid with the frame bar 15.

The medial cross bar 30 of the cradle is provided with a rearwardly projecting rigidly secured plate 40 that is arranged to rest upon the arched portion 32 of the supporting rod when such rod is in the upright position shown in Figs. 5 and 6.

A bolt 41 is rigidly secured to the bracket 38 and frame bar 15 and is slidable through a suitable perforation in the plate 40, which

bolt serves as a stop for the arched rod portion 32 and also serves to limit the upward movement of the cradle with respect to the carriage or frame.

The cross bars 25 at the upper extremity 70 of the cradle are connected by a U shaped bolt 42 with a lever arm 43 the rear end of which is urged upwardly by tension springs 44, only one of which is shown, that are adjustably secured to clips 45 on the cross bar 75 14. The forward end of the lever arm 43 projects beneath a lower brake shoe 46 and such lever arm is pivotally connected at a point a short distance to the rear of the brake shoe 46 with the lower member 47 of 80 a two part turnbuckle.

The upper member 48 of the turn buckle is pivotally connected with a lever arm 50 that is fulcrumed between bracket pieces 51 that are rigid with the frame 16 and that 85 extends crosswise of and rests upon brake shoes 52. The upper and lower brake shoes 52 and 46 respectively are both of somewhat flexible metal and have suitable extensions that are made fast to fixed portions of the frame, the upper brake shoe 46 being secured to a rigid bracket 53. The curved 90 brake portions of both the upper and lower brake shoes are lined with brake lining 54 that is disposed to frictionally engage with a brake drum or pulley 55 on a shaft 56 that is journaled in bearings 57 on the frame bars 14 and 16.

The forward end of the lever arm 43 is supported on a screw 58 when the brake is 100 not applied to the brake drum, said screw 58 being adjustably connected with a bracket 60 that is affixed to the frame bar 16.

The upper and lower portions 48 and 47 of the turn buckle are adjustably secured together by a bolt 49 which constitutes brake 105 adjusting means.

The drop carriage is supported for vertical movement in the drop shaft by a sprocket chain 62 that has one end secured as at 63, to an over head support 64, thence passes downwardly around a sprocket wheel 65 on the shaft 56, thence upwardly over an idler sprocket 66 on a shaft that is mounted on the over head support 64, thence downwardly around an idler sprocket 67 on the upper end of a counterweight 68 and thence upwardly to and is secured as at 70, to the over head support 64.

The counterweight 68 is guided for vertical movement by two T shaped track bars 71 that are supported in spaced apart parallel relation by rectangular brackets 72 that may be secured to the exterior of the wall 115 10 of the drop shaft.

A brake drum or pulley 73 is preferably secured to the shaft 69 on which the idler sprocket 66 is carried and a brake shoe 74 is arranged to rest upon and retard the rotation of the drum 73 said brake shoe being 120 125 130

arranged to have weights 75 removably placed thereon whereby the retarding effect of the same may be increased or diminished.

A relatively heavy chain 76 of substantially the same length as the drop shaft has one end secured to the bottom of the drop carriage and the other end secured to the counterweight 68 in the manner shown, so that as the drop carriage and counterweight move up and down the weight of the chain is gradually shifted from the downwardly moving member to the upwardly moving member.

The drop carriage is securely held in its uppermost position by a catch member 77 that is hinged to a stationary supporting member 78 and arranged to hook beneath a plate 79 that is secured to and projects rearwardly from the cross bar 25 at the top of the cradle. A compression spring 80 yieldingly urges the catch member outwardly and interlocking staple members 81 limit the movement of the catch member in response to the pressure of the spring 80. The lower end of the catch member extends downwardly and is bent into substantially the shape shown in Fig. 5, to form a trip arm 82 with which a stereotype plate 20 may engage to cause the catch member 77 to release the drop carriage.

Inwardly curved springs 83 of flat metal are secured to the trackways 11 near the upper end of the drop shaft to arrest the movement of the drop carriage as it approaches the uppermost position.

The drop carriage is retained in its lowermost position by a catch member 84 having hook elements 85 that are arranged to hook into a perforation or slot 86 in the front bar 21 of the cradle. The catch member 84 is normally held in an operative position by a tension spring 87 and is arranged to be moved outwardly to cause it to release the drop carriage by pivotally mounted foot lever 88 whose upper end engages the catch member 84 and whose lower end projects through the front wall of the front wall of the drop shaft. The upper end of the catch member 84 is curved, as shown, so that when the drop carriage descends the bar 21 will encounter said curved end and move the catch member outwardly.

A curved strip 90 is secured to the side wall of the drop shaft near the bottom thereof, as shown in Fig. 3, to form a slot 91 into which the roller 34 on the end of the member that normally supports the weight of the cradle and load may enter as the carriage nears the bottom of the shaft and a block 92 is provided near the top end of the curved strip to prevent the same from being abruptly deflected from its normal position.

In operation when the drop carriage is at the top of the shaft the catch member 77

will be hooked beneath the plate 79 and will hold the drop carriage in a fixed position so that a stereotype plate 20 may be easily inserted at the open front of the shaft placed on the cradle, as shown in Figs. 5 and 6, 70 and moved rearwardly until it strikes against the trip arm 82 and releases the carriage whereupon the combined weight of the stereotype plate, carriage and chain 76 will cause the carriage to descend rapidly until the roller 34 on the end of the rod member on which the cradle rests encounters the curved strip 90 and passes into the slot 91 near the bottom of the drop shaft, thus causing the arched portion 32 of the cradle 80 supporting rod to be moved out from under the plate 40, as shown in Fig. 8, so that the weight of the cradle and stereotype plate will be transferred and will hang from the lever arm 43 thus causing the linings 54 on the upper and lower brake shoes 52 and 46 to be applied to the brake drum 55 with sufficient force to arrest the downward movement of the loaded carriage and bring the same to a stop in such a position that the lower catch member 84 will engage within the slot 86 and lock the carriage in the lower position.

As soon as the stereotype plate 20 has been removed from the cradle the springs 44 will lift the weight of the cradle and release the brakes 46 and 52 so that when the catch member 84 is withdrawn from engagement with the carriage by depressing the lower end of the foot lever 88 such carriage will 100 be rapidly moved upwardly to the top of the shaft by the combined weight of the chain 76 and counterweight 68.

The weight of the chain 76 is shifted from the counterweight to the carriage and vice 105 versa as the counterweight and carriage move up and down, when the carriage is at the top of the drop shaft the major portion of the weight of the chain is suspended from said carriage and tends to pull the carriage 110 down when it is released but as the carriage descends the weight of the chain shifts to the counterweight thus tending to slow up the speed of descent of the carriage as it approaches the bottom of the drop shaft and 115 at the same time causing the chain to assume such a position that its weight will be effective in helping to start the carriage upward from the bottom of the shaft after the load has been removed therefrom. As the carriage approaches the upper end of the drop shaft in its upward movement the gradually shifting weight of the chain 76 causes the several parts to assume a substantially balanced relation and the speed 120 of movement of the carriage to be checked before it encounters the spring 83 and is stopped.

The brake 74 serves merely as a retarding means to insure a more even and uniform 130

movement of the various parts and to prevent the link belt 62 from being thrown off of the sprocket wheels over which it passes.

The set screw 58 and the bolt 49 in the turnbuckle that connects the lever arms 43 and 50 permit the brake mechanism to be adjusted to suit various loads and to regulate the speed of movement of the carriage.

The device is extremely rapid in operation and requires no power except that furnished by the weight of the article that is being lowered.

The foregoing description taken in connection with the accompanying drawings clearly discloses the plan of construction and method of operation of my invention, while I have shown and described what I now consider to be the preferred embodiment of my invention it will be understood that the disclosure is merely illustrative and that such changes may be made as are within the scope of the following claims.

What I claim is:

1. A device for lowering heavy objects including a carriage, a counterweight connected with said carriage, a cradle on said carriage arranged to receive a load, brake mechanism for retarding the movement of said carriage and means actuated by the weight of said cradle and its load for rendering said brake mechanism operative.

2. A device for lowering heavy objects including a vertically movable carriage, a counterweight connected with said carriage, a load receiving cradle movable in said carriage, releasable devices for normally supporting said cradle in a fixed position with respect to said carriage, brake mechanism mounted on said carriage and connected with said cradle whereby downward movement of said cradle on said carriage will apply said brake mechanism and means for automatically releasing said cradle supporting devices to permit said brake mechanism to be applied as said carriage approaches its lowermost operative position.

3. A gravity drop of the class described including a vertical elevator shaft, a carriage guided for movement in said shaft, a counterweight connected with said carriage, a load receiving cradle movably disposed within said carriage, releasable devices on said carriage for normally supporting said cradle, brake mechanism mounted on said carriage, suspension means connecting said brake mechanism and said cradle and means near the lowermost end of said elevator shaft for automatically releasing said cradle supporting devices whereby the weight of said cradle and its load will cause said brake mechanism to be applied as said carriage approaches the bottom of the elevator shaft.

4. A gravity drop of the class described including an elevator shaft, a carriage guided for movement in said shaft, a rigid frame

structure at the upper end of said elevator shaft, a counterweight, flexible devices connected with said frame structure and supporting said carriage and said counterweight for movement lengthwise of said elevator shaft, a brake drum mounted on said carriage and arranged to be rotated by said flexible carriage supporting devices as said carriage moves within said elevator shaft, brake shoes arranged to engage said brake drum, lever arms connected with said brake shoes, a load carrying cradle movably supported on said carriage and connected with said lever arms, means on said carriage for normally supporting said cradle and devices adjacent the bottom of said elevator shaft for moving said cradle supporting means to release said cradle and permit said cradle to hang from said lever arms and apply said brake shoes to said brake drum as said carriage approaches its lowermost operative position.

5. A gravity drop of the class described including a carriage, means for guiding said carriage for vertical movement, a shaft journaled in the upper portion of said carriage, a brake drum secured on said shaft, a pulley secured on said shaft, flexible carriage supporting means passing around said pulley and arranged to rotate said brake drum as said carriage moves up and down, brake shoes for said brake drum, a cradle movable on said carriage, releasable means for normally supporting said cradle and means connecting said cradle with said brake shoes and arranged to apply said brake shoes to said brake drum when said cradle supporting means is moved to release said cradle.

6. A gravity drop of the class described including a carriage, means for guiding said carriage for vertical movement, a shaft mounted for rotation on said carriage, a sprocket wheel secured on said shaft, a sprocket chain passing around said sprocket wheel and arranged to support said carriage for vertical movement, a counterweight connected with said sprocket chain, a brake drum on said shaft, brake shoes arranged to engage with said brake drum, lever means connected with said brake shoes, a load carrying cradle suspended from said lever means, springs connected with said lever means for supporting the weight of said cradle when the same is not loaded and for permitting said cradle to apply said brake shoes to said brake drum when said cradle is loaded and releasable means on said carriage for supporting said cradle independently of said brake means.

7. A gravity drop of the class described including a carriage, a shaft mounted for rotation on said carriage, carriage supporting means arranged to rotate said shaft as said carriage is moved vertically, a brake drum on said shaft, brake shoes disposed on

opposite sides of said brake drum, lever arms for applying each of said brake shoes to said brake drum, adjustable turnbuckle means connecting said lever arms, a load 5 carrying cradle movable vertically in said carriage, means connecting said cradle with one of said lever arms whereby weight on said cradle will tend to apply said brake shoes to said brake drum, resilient means 10 connected with said lever arms to counteract the weight of said cradle, a pivotally mounted arch like rod member mounted on said carriage below said cradle for supporting

said cradle when in an upright position, an outwardly protruding lever arm on said rod member, and means adjacent the path of movement of said carriage for engaging said outwardly protruding lever arm and turning said arch like supporting member into an inclined position to release said cradle 20 and apply said brake shoes to said brake drum.

In witness whereof, I hereunto subscribe my name this 1st day of March A. D. 1922.

JOHN DOWNIE.
